UNITED STATES PATENT OFFICE.

BENJAMIN F. ORTON, OF EAST SAGINAW, MICHIGAN.

ARMATURE FOR DYNAMO-ELECTRIC MACHINES.

SPECIFICATION forming part of Letters Patent No. 309,735, dated December 23, 1884.

Application filed December 11, 1883. (No model.)

To all whom it may concern:

Be it known that I, BENJAMIN F. ORTON, a citizen of the United States, and a resident of East Saginaw, in the county of Saginaw and State of Michigan, have invented certain new and useful Improvements in Armatures for Dynamo-Electric Machines, of which the following is a specification.

My invention relates to the construction of the core or carrier upon which the armature coils or bobbins of a dynamo-electric machine or motor are wound.

The object of my invention is primarily to increase the efficiency of the machine, but also to so construct the armature core or carrier that it shall constitute what is known as a "sectional" armature, or one in which the armature ring or cylinder may be built up from sections upon or to which coils or bobbins have been previously wound or applied.

My invention is intended to provide a simple construction for this purpose, and at the same time to prevent the circulation of so-called "Foucault" or induced currents in the body of the armature ring or core.

My invention consists in certain details of construction and combinations of parts, that will be hereinafter described, and then specified in the claims.

In the accompanying drawings, Figure 1 is a longitudinal section of one of the armature-segments on the line 1 1 of Fig. 2. Fig. 2 is a transverse section on the line 2 2 of Fig. 1. Fig. 3 is a longitudinal section showing the manner of applying a retaining band or strip to the core. Fig. 4 is a side view of a portion of a ring-armature constructed according to my invention. Fig. 5 is a transverse section through one of the arms of the frame or spider upon which the armature segments are supported and to which they are secured. Fig. 6 is a plan view of an armature-coil and a portion of the core. Fig. 7 is a section on the line 3 3 of Fig. 3. Fig. 8 is a side view of the devices employed for fastening the abutting sections together when the construction of Fig. 3 is employed. Fig. 9 is a longitudinal section of an armature, showing a modified disposition of the thin curved strips or plates constituting the body of the armature. Figs.

10 and 11 illustrate a form of armature-section to which the frame or spider of Figs. 4 and 5 is adapted.

Referring to Figs. 4 and 5, A indicates the hub of the frame or spider, from which hub project the four arms or spokes B, each of which latter is widened at its top and in a direction parallel to the axis of the machine, to form an extended bearing or seat, C, upon which the abutting ends of the armature segments or sections rest. The bearing C is slightly recessed by preference, as shown in Fig. 5, to prevent lateral movement of the armature-sections. The abutting ends of the sections are clamped or held in place by a yoke or a cross-piece, D, extending across from one side of the armature to the other, and bolted or otherwise secured to the seat or bearing C, as indicated in Fig. 5. The main portion of each armature-section is made up of a series of thin sheets of iron, e, which are curved or bent to the general form of the armature, and are piled upon one another, as shown in Figs. 1 and 2, and are clamped together and secured to a curved base piece or support, d, also of iron, but somewhat thicker and heavier than the plates e, so as to form a stiff support or tray or holder for the latter. The trays or holders d abut and rest squarely against one another, and are supported in the seats C, as indicated in Fig. 4, in which position they are held by the cap-plates D. Each plate e is made somewhat shorter than d, so as to leave a space between one end of each plate e and the adjoining end of d, thus preventing in large measure the circulation of induced currents in the body of the core or carrier. The plates e are separated from one another by plates or washers of iron, so as to leave passages between the plates e for the circulation of air. Thin pieces of non-magnetic material may be interposed between the separating-washers and the plates e, so as to electrically insulate the plates e from one another, and prevent the flow of the induced currents transversely in the core. The plates e and d are held together by rivets f or other device.

F F F, &c., indicate pieces of thin sheet metal or other suitable material bent up into the shape shown, so as to form guides or hold-

ers for the armature-wires, and clamped to the inner and outer sides of the armature-core by the rivets *f* or other devices.

At *g g g*, &c., are indicated lugs or projections extending from the inner side of the plate or holder *d*, and serving to determine the position of the inner guide-pieces *F*, as well as to prevent the latter and the coils upon them from slipping upon the core. Lateral projections *h* aid in keeping the coils in place. The projections *g* and *h* at the extremities of the plate *d* abut against the edges of the seats or bearings *C*, and prevent the armature-core from slipping in said bearings.

15 In addition to the inner plates or supports, *d*, I sometimes use a retaining-band made up of a number of curved plates, *m*, of any suitable material, preferably iron, which lie upon or form the exterior portion of the core, as shown in Figs. 3, 7, and 8. The upturned ends of the latter are bolted together, and the ends of said plates by preference rest upon the upturned ends of the plates *d*. In this case the clamp *D* is cut away at its center, as shown in Fig. 7, to leave space for the plates *m*, forming the exterior clamping-band. The ends of the plates *d* are planed or milled, so that they will abut squarely, and thus make good magnetic connection from one section of the armature to the other. When the exterior band, *m*, is of iron, the arrangement of it and the plates *d* (shown in Fig. 3) conduces to good magnetic continuity of the armature-core.

35 I have in the drawings shown the armature as made in four sections or segments; but it will be of course understood that each section may be much shorter and their number correspondingly increased, there being in such case a correspondingly large number of seats or bearings *C*. I have also shown a multiplicity of armature-coils upon each armature segment or section; but, if desired, there may be a separate armature-segment for each coil. 40 The seat or bearing *C*, as it extends transversely the entire width of the armature-core, forms a stable and firm support for the armature-segments, and the structure, when the various segments are put in place and clamped 45 by the yokes or cap-pieces *D*, forms a complete armature of great stiffness and rigidity. At the same time any segment, with its coil or coils, may be readily removed for any purpose.

55 In Fig. 9 the thin curved strips of iron, *c*, are much shorter than the supporting plate or tray *d*; but their ends are made to overlap, so that a free air-space is left, as indicated, between the plates. Separating plates 60 or washers are interposed at suitable points. Comparatively thin washers or plates may be interposed between the overlapping ends of the plates *c*, while at or near the ends of the plates *d* thicker pieces are interposed, to keep 65 the plates *c* the requisite distance apart. The plates *c* are also by preference electrically in-

sulated by interposing thin sheets of paper or other suitable material at the proper places, as is well understood in the art.

The supporting frame or spider and the 70 clamping-plates *D* are well adapted to holding and securing armature-core sections of the construction indicated in Figs. 10 and 11, in which the thin sheet-metal strips are set on edge and rest directly at their ends in the 75 seats or bearings *C*. The plates *c* of Fig. 10 are secured together by transverse bolts, as shown, and are separated from one another by thin washers, as indicated, of any desired material.

80 *H H H* indicate stiffening-plates, made somewhat thicker than the plates *c*.

What I claim as my invention is—

1. In a sectional armature, segments or sections, each consisting of a curved base or 85 supporting plate constituting a segment of a circle, carrying a number of superimposed sheets of iron with interposed separating plates or washers.

2. In a sectional armature, a segment or 90 section composed of a tray-like holder or support, *d*, having upturned ends, and carrying a number of superimposed thin plates of iron.

3. A sectional armature composed of segmental base plates or supports of iron having 95 upturned ends that abut against one another, and each carrying a number of superimposed thin plates of iron secured together and to said base-plate.

4. In a dynamo-electric machine, the combination, with the abutting ends of the armature-sections, of a seat or bearing, *C*, extending the width of the armature-section, and a transverse clamping-plate or cap-piece, *D*.

5. In a dynamo-electric machine, a frame 105 or spider for holding the segments or sections of a sectional armature, having the seats or bearings *C* of a width corresponding to the width of the armature-core, in combination with armature-segments having their abutting 110 ends resting on said seats, and means for holding said abutting ends in position.

6. In a dynamo-electric machine or motor, a retaining band or ring for the armature, made of segments *m*, having upturned ends 115 bolted or otherwise properly secured together.

7. The combination of the abutting supporting-plates *d*, the exterior retaining-plates, *m*, bolted together, and a series of superimposed thin sheets of iron held between each 120 pair of plates *d m*, and separated from one another by free air-spaces.

8. The combination of the supporting-plates *d*, having upturned ends resting in contact, and held in place upon a spider or by any 125 suitable construction, the exterior retaining-plates, *m*, resting at their ends upon the abutting ends of the plates *d*, and secured by any suitable means, and the series of thin iron plates *c*, superimposed, but separated by free 130 air-spaces.

9. In an armature for dynamo-electric ma-

chines or motors, the combination of the superimposed thin segmental strips of iron, *e*, rivets or bolts *f*, and separating-pieces of iron between said strips, as and for the purpose described.

- 5 10. In a sectional armature, a curved base-plate for an armature-section, said base-plate having upturned ends, as and for the purpose described.
- 10 11. In a dynamo-electric machine or motor, a ring or cylinder armature built up from thin plate-iron in superposed layers bent or curved to the form of the armature, and having interposed separating-pieces of magnetic material 15 for separating the superposed layers, so as to

leave transverse or lateral air-spaces through the body of the armature.

12. In a dynamo-electric machine or motor, an armature built up from thin superimposed iron plates bent to the form of the armature 20 and separated from one another by lateral free air-spaces.

Signed at New York, in the county of New York and State of New York, this 7th day of December, A. D. 1883.
